UNITED STATES PATENT OFFICE.

FRANZ LÖSEL, OF BRUNN, CZECHOSLOVAKIA.

STEAM TURBINE.

Application filed July 17, 1924, Serial No. 726,459, and in Austria July 31, 1923.

This invention relates to elastic fluid turbines, and particularly such as steam and gas turbines for propelling motor driven vehicles, locomotives, ships and other moving craft.

An object of the invention is to provide an improved turbine of this type which is capable of a more ready and efficient control than prior turbines, and especially a turbine possessing novel features of construction and operation by which its rotation and operation may be quickly retarded and arrested with facility, and if desired its operation reversed. To this end I have devised a turbine, having certain of its rotating wheels and stationary diaphragms and guide nozzles therein provided with blades for both forward and backward rotation, with a separate admission of elastic fluid for the reversing canals, whereby after the power is shut off from the forward driving canals, the machine may be effectively braked and quickly brought to rest by admitting steam to the same stages or a part of the same stages, but only to the reversed blades. My invention further contemplates certain particular and correlated relative arrangements of both forward and backward guide nozzles and buckets, in the same turbine stage or stages with special admission and exhaust connections, adapted for different exhaust or discharge conditions and being provided for such purposes with separate and independent discharge or exhaust outlets for forward and backward turbine fluid flow, as will hereinafter appear. Other objects and advantages will hereinafter appear.

For a better understanding of my invention, reference may be had to the accompanying drawings forming a part of this application, wherein:

Fig. 1 is a longitudinal sectional view of a turbine embodying one form of my invention, and

Figs. 2-5 inclusive are similar views of turbines embodying modifications of the invention.

Referring to Fig. 1 of the drawings, I have indicated my invention as embodied in a turbine consisting of a rotor *a* carrying the rotating discs *c* and enclosed by the casing *b* with the diaphragm and guide nozzle members *d* carried by the casing *b* and situated between the rotor discs *c*. The ad-

mission for the elastic fluid is indicated at *k* from whence the steam flows through the rotating canals or cells *e* carried by the rotating discs *c* and the stationary guide nozzles *h* carried by the diaphragms *d*. The exhaust chamber or low pressure end of the turbine is designated by the letter *m*. In certain of the diaphragms *d* and the rotating discs *c* there are provided auxiliary guide nozzles *g* and rotating canals *f*. In Fig. 1 there is indicated a rotating canal *f* on the first or high pressure disc *c* which is conveniently situated just above the rotating canal *e* and in the next succeeding diaphragm *d* there is a corresponding stationary auxiliary guide nozzle *g* for guiding driving fluid into the canal *f*. An entrance or admission *l* is provided for the driving fluid entering the guide nozzle *g*. The additional or auxiliary guide nozzles *g* and cells *f* are so constructed as to tend to drive the rotor *a* in the opposite direction when the steam is passed therethrough to the direction of rotation when the steam passes through the corresponding guide nozzles and rotating canals *h* and *e*. For normal working, as for example full forward driving of the vehicle or craft that is being propelled by the turbine, the driving fluid passes through the admission *k* and from thence successively through the rotating canals *e* and guide nozzles *h* as in ordinary turbine practice, and causes a transformation of the elastic fluid energy into mechanical energy by rotation of the rotor *a* in one direction. If it is desired to exert a retarding or braking of the rotor *a*, steam is then admitted through the admission *l* and passed through the stationary guide nozzles *g* of the first diaphragm *d* and from thence through the rotating canals *f*; steam thus admitted and passing through the turbine in this manner tending to oppose the rotation of the rotor. If the driving steam is at the same time entirely shut off on the admission *k* the admission of working steam to the nozzles *g* and canals *f* will result in the very quick and rapid slowing up or stopping of the rotor *a* and of course if such steam flow is continued after a complete standstill is reached, a backward rotation of the turbine may be effected. It may be desirable in certain cases to only partially shut off steam supply to admission *k* while steam is admitted through *l*.

The braking effect and the driving force in the opposite direction are dependent, of course, upon the number and dimensions of the reversed guide nozzles *g* and the rotating canals *f*. In Fig. 1 I have shown these auxiliary reversed guide nozzles and rotating canals as disposed respectively on the first rotating disc and the next succeeding diaphragm for one stage of the turbine.

10 These backward rotation or brake guide nozzles and rotating cells may be provided in as many stages as are desired in practice, and in Fig. 2 I have shown these auxiliary guide nozzles and rotating canals as provided in the first two disc wheels and the two corresponding diaphragms. Ordinarily the steam for causing a braking or backward rotation of the turbine may conveniently be taken from the main steam supply 20 leading to the admission *h* and brought in through the admission *l*, but if desired a fluid of different pressure than that admitted to admission *h* or an entirely different character of elastic fluid may be employed, 25 if desired.

In Figs. 1 and 2 the working fluid for the reversed guide nozzles and rotating canals exhausts into the chamber leading directly to the normal working canals *e*. I have 30 indicated in Fig. 3 a separate exhaust chamber *n* leading to exhaust or bleeder pipes *o* for exhausting the whole or a portion of the braking or backward rotation steam coming through the last rotating canal *f*. 35 This arrangement would be particularly preferable for backward rotation or operation of the turbine.

Instead of devising a multistage turbine 40 with the reversed guide nozzles and rotating cells at the high pressure end of the turbine casing, these may be provided at any other points of the turbine, as for example at the low pressure end indicated in Fig. 4. According to this embodiment of the invention the turbine casing is provided with an intake *l* leading to the stationary guide nozzles *g* and the rotating canals *f* and from thence to the exhaust chamber *n* out through the exhaust pipe *o*.

50 In Figs. 1 to 4 inclusive the steam for causing the braking or backward rotation of the turbine rotor is indicated as flowing oppositely to the direction of the steam passing through the turbine for forward operation thereof, the guide nozzles *g* and *h* and the rotating canals *e* and *f* being arranged to necessitate such opposite flow of steam, but in Fig. 5 I have illustrated a different relative arrangement of guide nozzles and 60 rotating canals which permits the flow of steam in the same direction through the turbine both for normal or forward operation and for the retardation or braking operation. When this arrangement is in the last 65 stages, the exhaust *m* may be used in certain

cases for the steam of the backward turbine, too.

By means of my invention illustrated in the various figures, as above defined, it is clear that I have devised an effective and 70 a quick braking or retardation arrangement for turbines with novel features. Such braking or retardation being effected easily and with the greatest facility without injury to the turbine parts and without the 75 necessity for other expensive and inefficient braking devices. Moreover, the necessity for separate backward turbines with special separated wheels and casings is avoided, the various functions of retarding, braking and 80 backward rotation being effected by the single turbine rotor and diaphragms with the reversed guide nozzles and canals disposed in the rotating wheels and stationary guide means. I have thus devised a single readily 85 brakable reversible steam turbine having separate forward and backward guide nozzles and canals which are incorporated into the same rotor and guide elements and within the same casing. My invention is applicable to different types of turbines. 90

Having thus described my invention, the following is claimed:

1. In an elastic fluid multi-stage turbine, the combination of rotating disc carrying 95 rotating canals and stationary diaphragms having guide nozzles for the reception of the elastic fluid for one direction of rotation, one of said disc wheels having auxiliary rotating canals radially outwardly 100 disposed with reference to the main set of canals for effecting opposite rotation of the turbine rotor, and one of said diaphragms having corresponding radially outwardly 105 disposed auxiliary guide canals adapted to conduct the elastic fluid to the auxiliary rotating canals and a casing housing the rotating wheels and carrying the stationary diaphragms of the turbine, said casing including at an intermediate stage thereof a radially 110 disposed passage through which the steam for the auxiliary circuit including the guide canals and rotating canals passes.

2. In an elastic fluid multi-stage turbine of the disc wheel type, the combination of 115 single rotating wheels having rotating canals, and diaphragms having stationary guide nozzles for the reception of elastic fluid for one direction of rotation, one of said disc wheels having radially outwardly 120 disposed auxiliary rotating canals for reverse rotation and one of said diaphragms having auxiliary guide canals adapted to conduct elastic fluid through said stationary and rotating auxiliary canals for opposing 125 the forward movement of the turbine and forming, with the canals in a separate diaphragm, two steam circuits provided with separate exhaust chambers and a casing housing both the rotating wheels and carry- 130

ing the diaphragms and having a radially disposed passage through which the steam for the auxiliary rotating canals passes.

3. In an elastic fluid multi-stage turbine of the disc wheel type, the combination of single rotating wheels having rotating canals and diaphragms having stationary guide nozzles for the reception of elastic fluid for one direction of rotation, one of said disc wheels having radially outwardly disposed auxiliary rotating canals for reverse rotation and one of said diaphragms having auxiliary guide canals adapted to conduct elastic fluid through said stationary and rotating auxiliary canals for opposing the forward movement of the turbine, the steam circuits including the passages that direct the elastic fluid for direct and reverse rotation being provided with separate admissions and separate exhaust chambers and separate independent outlet or discharge passages leading from said exhaust chamber and a cylindrical housing for said rotating wheels including a radially disposed passage.

4. In a multistage elastic fluid turbine of the disc wheel type, stationary diaphragms having guide nozzles, rotor disc wheels having rotating canals for normal operation in one direction, said diaphragms having radially outwardly disposed auxiliary stationary guide nozzles for said rotating canals,

said rotor wheels also having rotating canals in a number of stages for effecting a retarding dragging effect upon the rotor, and 35 elastic fluid guiding means having a separate admission and a separate exhaust including a separate independent discharge or outlet passage for the steam retarding circuit and a cylindrical housing for said turbine having a radially disposed passage for the steam retarding circuit. 40

5. In a turbine of the elastic fluid type having rotating wheels and diaphragms therebetween, the combination of a diaphragm having two sets of separate stationary canals, one set of said stationary canals being auxiliary to and outwardly radially disposed with reference to the canals for normal operation in the diaphragm and said auxiliary canals being directly connected with an auxiliary fluid passage including a radially disposed passage through the turbine casing, a rotor wheel in the same stage 50 of the turbine and provided with two sets of rotating canals for forward and reverse rotation, and means including a casing portion having separate fluid admission passages to direct driving fluid to said sets of rotating canals respectively. 55 60

In testimony whereof, I have signed my name to this specification.

FRANZ LÖSEL.

CERTIFICATE OF CORRECTION.

Patent No. 1,618,596.

Granted February 22, 1927, to

FRANZ LÖSEL.

It is hereby certified that error appears in the printed specification of the above numbered patent requiring correction as follows: Page 2, line 95, claim 1, after the word "disc" insert the word "wheels"; and that the said Letters Patent should be read with this correction therein that the same may conform to the record of the case in the Patent Office.

Signed and sealed this 22nd day of March, A. D. 1927.

Seal.

M. J. Moore,
Acting Commissioner of Patents.
